UNITED STATES PATENT OFFICE.

LESTER C. HART, OF CLEVELAND, OHIO, ASSIGNEE TO HI-VOLTAGE EQUIPMENT COMPANY, A CORPORATION OF PENNSYLVANIA.

LIGHTNING ARRESTER.

Application filed June 2, 1921. Serial No. 474,475.

To all whom it may concern:

Be it known that I, LESTER C. HART, a citizen of the United States, and a resident of Cleveland, in the county of Cuyahoga and State of Ohio, have made a new and useful Invention in Lightning Arresters, of which the following is a specification.

The invention relates to what are known as lightning arresters, such term comprehending devices for protecting power lines from surges of current produced by various causes, not only by lightning but by static, high frequency impulses, and switching or other causes which impose upon the line an excess of voltage which must be relieved in order to protect the line and the apparatus connected thereto from injury. In apparatus of this general character it has been the practice to provide a relief circuit to the ground including a horn gap and resistance. The gap prevents any loss of current under normal conditions, but when a surge of current is imposed upon the line and of such a character that it might injure the line or the apparatus connected thereto, an arc is produced across the gap and the current conducted through the resistance to the ground, such arc being broken automatically by the lengthening of the arc due to its upward movement on the diverging horns or discharge members at opposite sides of the gap. The normal current in the supply line tends to continue the arc after the crest of the surge has passed the gap to the ground and it is this current which is generally responsible for any injury to the resistance in the relief circuit. If the gap in the relief circuit is lengthened in order to reduce the time which the arc continues, the sensitiveness of the device is reduced since the surge must be built up to a higher point before the arc is made, so that the supply circuit lacks the protection which it would have with a shorter gap.

It is the purpose of the present invention to provide an arrester which will respond quickly to surges of moderate intensity, but which will at the same time provide for the interruption of the arc formed and the power current following and continuing such arc in a minimum interval of time. These primary objects and others which will more fully appear will be more readily under

stood after a consideration of the following description and of the drawings which illustrate one form of the invention wherein;

Figure 1 is a side elevation of the assembled apparatus, and Fig. 2 is an enlarged section on the line II-II of Fig. 1.

Referring to the drawings, 1 is a base of any suitable construction upon which are mounted the three insulator pins 2, 3 and 4 carrying the insulators 5, 6 and 7. The insulator 5 carries the horn gap bar 8, the insulator 6 carries the pair of horn gap bars 9 and 10, while the insulator 7 carries a fourth horn gap bar 11 in opposition to the bar 10. The opposing bars 8 and 9 provide one discharge gap while the opposing bars 10 and 11 provide a second gap, such second gap being relatively much shorter than the one between the bars 8 and 9. Between the bar 11 and the wire 12 leading to the ground is a suitable resistance carried by the casing 13. The bar 8 at the other end of the apparatus is provided with the lead connection 14 by means of which the apparatus is connected to the power circuit which is to be protected.

Intermediate the bars 8 and 9 is a member 15 which may be termed a flash rod, such member providing a relatively high resistance connection between the two bars. This rod may be constructed in a variety of ways but preferably consists of a fiber core 16 (Fig. 2) surrounded by a tubular bar 17 of porcelain. The upper half of this bar is provided with a relatively thin coating 18 of carborundum although other material may be used in this coating such as flake metals or small particles of conducting material.

The arrester as illustrated and described has a number of advantages as compared with the ordinary lightning arrester, having only the single discharge gap and lacking the flash rod feature. In the first place it is relatively sensitive. The action is rapid in that the flash rod promotes the quick formation of an arc across the longer gap while the discharge across the shorter gap is relatively quick because of the short distance, so that the excess voltage on the power line may be relieved in a minimum element of time. The flash rod promotes the formation of the arc as a flow of current can pass between the two horn rods 8 and 9 due to the

conductivity of the coating on the flash rod and the arc will follow the flow thus set up since the capacity of the flash rod is of course much below the load imposed by a heavy surge of current such as the arrester is designed to take care of

In the second place the arrester promotes the return to normalcy as soon as the crest of the surge is past since the relatively long gap between the horn members 8 and 9 causes a quick break as soon as the main intensity of the discharge has passed along. As a result the power current which follows the surge flows through the resistance 13 a minimum length of time. It is the flow of the power current through this resistance which tends to injure the resistance so that a rapid breaking of the power current affords great protection against injury to the arrester. This rapid return to normal condition not only permits the arrester to take care of surges which occur close together but also prolongs the life of the arrester for the reason above explained and incident to the reducing of the flow of current through the resistance to a minimum element of time. The provision of the sphere members on the horn members 10 and 11 materially assist in increasing the speed of discharge across the gap.

The use of the relatively long gap with the flash rod in connection with the short gap also permits static, which on many systems causes a large percentage of arrester discharges, to drain across the flash rod and to the ground without causing any power arc as the line current will not follow to the ground under these conditions. Another advantage incident to this arrester lies in its adaptability since the design is such that it may be easily, safely and economically mounted with the average installation, and when in service will not require attention other than the regular inspection that equipment of this general character is given, the apparatus being relatively free from injury and consequently of long life for the reasons above set forth.

Other advantages incident to the construction will be readily apparent to those skilled in the art.

What I claim is:

1. In a lightning arrester, the combination with a power circuit, of a relief or discharge circuit leading to the ground and comprising a pair of discharge gaps of different length each including a pair of opposing discharge members, and a conductor of relatively high resistance lying in the wider gap and connecting the opposing discharge members of such gap.

2. In a lightning arrester, the combination with a power circuit, of a relief or discharge circuit leading to the ground and comprising a pair of horn gaps of different length, and

a conductor of relatively high resistance lying in the wider gap and connecting the opposing horns of said gap.

3. In a lightning arrester, the combination with a power circuit, of relief or discharge circuit leading to the ground and comprising a pair of discharge gaps of different length each comprising a pair of opposing discharge members with a rod of insulating material directly connecting the opposing discharge members of the wider gap, such rod having a coating of conducting material

4. In a lightning arrester, the combination with a power circuit, of relief or discharge circuit leading to the ground and comprising a pair of discharge gaps of different length each comprising a pair of opposing discharge members with a rod of insulating material directly connecting said discharge members of the wider gap, such rod having a coating of conducting material on the side only adjacent said horns.

5. In a lightning arrester, the combination with a power circuit, of relief or discharge circuit leading to the ground and comprising a pair of discharge gaps of different length each comprising a pair of opposing discharge members, with a refractory conductor of relatively low capacity directly connecting the opposing discharge members of the wider gap.

6. In a lightning arrester, the combination with a power circuit, of relief or discharge circuit leading to the ground and comprising a pair of horn gaps of different length, with a refractory conductor of relatively low capacity directly connecting the opposing discharge members of the wider gap.

7. In a lightning arrester, a horn gap, comprising two opposing horn rods, and a rod of insulating material between such rods having a coating of conducting material connected to said horn rods.

8. In a lightning arrester, a horn gap, comprising two opposing horn rods, and a rod of insulating material between such rods having a coating of refractory conducting material connected to said horn rods.

9. In a lightning arrester, a horn gap, comprising two opposing horn rods, and a rod of insulating material between such rods having a coating of material of relatively low conductivity connected to said horn rod.

10. In a lightning arrester, a horn gap, comprising two opposing horn rods, and a rod of insulating material between such rods having a coating of conducting material extending only partially around the circumference of the rod.

11. In a lightning arrester, a horn gap comprising two opposing horn rods, and a rod of insulating material between such rods having a coating of conducting ma-

terial extending only partially around the circumference of the rod with the side of the rod remote from the horn rods uncoated.

12. In a lightning arrester, the combination with a power circuit, of a relief or discharge circuit leading to the ground and comprising a pair of discharge gaps of different length, each including a pair of opposing discharge members, and a bar of insulating material lying in the wider gap between the opposing discharge members of such gap, and provided with a thin coating of carborundum.
13. In a lightning arrester, the combination with a power circuit, of a relief or discharge circuit leading to the ground and comprising a pair of discharge gaps of different length, each including a pair of opposing discharge members, and a bar of insulating material lying in the wider gap between the opposing discharge members of

such gap, and provided with a thin coating consisting of fine particles of conducting material.

14. In a lightning arrester, a discharge circuit leading to the ground and having a discharge gap therein, and a rod of insulating material bridging the gap and provided with a thin coating of carborundum. 25

15. In a lightning arrester, a discharge circuit leading to the ground and having a discharge gap therein, and a rod of insulating material bridging the gap and provided with a thin coating consisting of finely divided conducting material. 30

In testimony whereof, I have hereunto subscribed my name this 27th day of May, 1921.

LESTER C. HART.
